S. ROSENBLUM

HOOK FOR PICTURES AND THE LIKE

Filed Jan. 6, 1925

Samuel Rosenblum, INVENTOR

BY
Robert S. Killgoar
ATTORNEY

UNITED STATES PATENT OFFICE.

SAMUEL ROSENBLUM, OF NEW YORK, N. Y.

HOOK FOR PICTURES AND THE LIKE.

Application filed January 6, 1925. Serial No. 807.

To all whom it may concern:

Be it known that I, SAMUEL ROSENBLUM, a citizen of the United States, residing at New York city, in the county of New York 5 and State of New York, have invented certain new and useful Improvements in Hooks for Pictures and the like, of which the following is a specification.

My invention relates to hooks for hanging pictures, mirrors, tapestries, draperies and the like and it is my object to produce a simple, unitary hook which may be used either on a picture moulding or on a nail, screw or hook driven into the wall.

15 In the drawing Fig. 1 is an edge view of my improved hook on a moulding; Fig. 2 a front view of my improved hook; Fig. 3 an edge view of the hook on a nail; Fig. 4 a rear view of the hook in position to engage 20 a nail, screw or hook; and Fig. 5 a detail view of the upper portion of my improved hook.

As shown in the drawing my improved hook is made of two parts permanently 25 hinged together into a unitary article of manufacture. The first part, or body, 1 has a hook 2 to engage a picture or mirror cord or a tapestry or drapery. The second, or upper portion, 3, which engages either a picture moulding or a nail, screw or hook in the wall or other surface, has two notches 30 4—4, with a forwardly extending stop 5.

The upper end of the body 1 has a slot 6 (best shown in Figs. 2 and 4) with which 35 the notches 4—4 engage, the stop 5 lying in front of the body 1. As shown in the drawing the slot 6 is cut out at the top so that the ears can be bent to allow the notches 4—4 to enter it, after which the ears are bent 40 back to close the slot and permanently unite the two parts.

The upper portion 3 has a key-hole slot 7 in its rear face, with the enlargement in the bottom, when the upper part 3 is turned 45 down.

If the hook is used on a moulding the part

3 is turned up and hooked over the moulding in the usual manner, the stop 5 limiting its forward movement. If used on a nail, screw or hook the part 3 is turned down and 50 the keyhole slot slipped over the head.

The invention permits the same hook to be used on either a moulding or on a nail, screw or hook by merely turning the upper part either up or down and it is cheaply 55 made and simple to use in either position, holding solidly when once in place. As the hook is a unitary structure there are no separate parts to assemble or disassemble or become separated and lost. 60

I claim:—

1. As a new article of manufacture, a picture hook comprising a body provided with a slot near its upper end, a hook at the lower part adapted to engage a picture cord 65 or the like, and an upper hook portion, notched in its lower side edges engaging the slot in the body whereby the upper portion may be turned down to engage a fastening device or up to engage a picture moulding, 70 said upper portion being provided with a longitudinal slot adapted to engage a fastening device.

2. As a new article of manufacture, a picture hook comprising a body provided with 75 a slot near its upper end, a hook on the lower part adapted to engage a picture cord or the like, and an upper hook portion, notched in its lower side edges, engaging the slot in the body, the end of the upper 80 portion being forward of the body and adapted to engage the same as a stop, said upper portion being provided with a longitudinal slot in the hook adapted to engage a fastening device whereby the upper portion 85 may be turned down to engage a fastening device or up to engage a picture moulding.

In testimony whereof I have affixed my signature.

SAMUEL ROSENBLUM.
